VIBRATION ELIMINATOR FOR PRESSURE REGULATORS

Anton Salmonsen, Great Kills,
Staten Island, N. Y.

Application May 27, 1944, Serial No. 537,688

4 Claims. (Cl. 50—26)

1

My invention relates to air, gas, water, steam and oil pressure regulators, and has among its objects and advantages the provision of an improved vibration eliminator.

In the accompanying drawing:

Figure 1 is a vertical longitudinal sectional view of a conventional pressure regulator embodying my invention.

Figure 2 is a face view of the vibration eliminator, and

Figure 3 is an edge view.

In the embodiment of the invention selected for illustration, Figure 1 illustrates a pressure regulator comprising a lower casing 10 and a dome 12 between which a diaphragm 14 is clamped, the casing 10 and the dome 12 being fixedly secured one to the other by bolts 16. The casing 10 includes a boss 18 internally threaded at 20 for connection with a fluid supply pipe, not shown. The casing also includes a wall 22 through which is threaded a valve orifice 24. A valve 26 is seatingly related to the valve orifice 24 and is connected with one end of a lever 28, this lever being pivotally supported at 30 in the casing 10.

The other end of the lever is pivotally connected at 34 with a lever plate 36 between which and a weight plate 38 is clamped the diaphragm 14, although the surrounding portion of the diaphragm is free to flex in response to variable pressure conditions effective thereon. A compression spring 40 has one end mounted on a post 42 located centrally of the weight plate 38, the other end of the spring having abutting engagement with a plug 44 threaded into a boss 46 on the dome 12. This plug may be adjusted to vary the tension of the spring 40. A cap 48 provides a closure for the boss.

A second boss 50 is provided on the dome 12 and is internally threaded at 52 for connection with an outlet conduit not shown. The incoming fluid enters the boss 18 and leaves through the boss 50, the flow of the fluid causing a pressure inside the casing 10 and the diaphragm 13 being responsive to such pressure. The construction so far described is old and well known in the art.

My invention comprises a vibration eliminator 54. While the vibration eliminator shown in the accompanying drawing comprises three equally spaced radial stems 56, it may comprise any required number of stems, the number and relative spacing of the stems depending upon the action of the regulator. The stems 56 are attached to the post 42 and are arranged in a

2

plane paralleling the weight plate 38. To the outer ends of the stems 56 are pivotally connected eccentrics 58, all the eccentrics being of the same size, weight and shape. The eccentrics are arranged at right angles to their respective stems 56, and the pivotal connection between the eccentrics and the stems are located at the ends of the eccentrics.

Each eccentric includes a curvature 60 engaging the upper face of the weight plate 38, these curvatures being located intermediate the ends of the respective eccentrics, but remote from the free ends thereof, as shown in Figure 3, the opposite edges of the eccentrics are curved at 62 adjacent their free ends for engagement with the inner face of the dome 12.

My invention maintains practically a constant pressure at more than one point on the top of the regulator diaphragm since the spring 40 rests on the post 42. The curvatures 60 are spaced 120 degrees apart and apply adjustment spring tension at three equally spaced points circumferentially of the axis of the diaphragm, to maintain a stiffening force at these points between the flexible diaphragm and the rigid dome 12, thereby preventing vibration of the diaphragm and the regulating valve.

The invention operates as a stiffening device, to be inserted between the flexible diaphragm 38 and the rigid body of a regulator, to eliminate the characteristic vibration of the flexible diaphragm and valve, thus eliminating the objectionable noise and the rapid wearing of the valve face.

Without further elaboration, the foregoing will so fully explain my invention, that others may, by applying current knowledge readily adapt the same for use under various conditions of service.

I claim:

1. In a fluid pressure regulator, the combination of a housing having a fluid inlet and a fluid outlet, a flow controlling valve, a pressure responsive diaphragm inside said housing operatively connected with said valve, a diaphragm vibration eliminator means yieldingly exerting pressure at a plurality of points on said diaphragm, said diaphragm vibration eliminator means comprising a plurality of stems fixedly connected to one another, eccentric members movably mounted on said stems, and resilient means interposed between said stems and the housing, said eccentric members having curved contours respectively engaging the diaphragm and the housing.

2. In a fluid pressure regulator, the combination of a housing having a fluid inlet and a fluid outlet, a flow controlling valve, a pressure respon-

sive diaphragm inside said housing operatively connected with said valve, a weight plate engaging one face of said diaphragm, a hub, stems attached to said hub, eccentric members rotatably mounted on said stems and respectively engaging said weight plate and said housing, and a tensioning spring interposed between said housing and said hub to yieldingly urge said eccentric members into said engagement with said weight plate.

3. In a fluid regulator, the combination of a housing having a fluid inlet and a fluid outlet, a flow controlling valve, a pressure responsive diaphragm inside said housing operatively connected with said valve, a diaphragm vibration eliminator means yieldingly exerting pressure at a plurality of points on said diaphragm, said means comprising a body having a plurality of radial stems attached thereto and spaced equal distances

apart, eccentric members rotatably mounted on the outer ends of the stems and having curved faces respectively engaging the diaphragm and said housing, and a tensioning spring interposed between said body and said housing.

4. In a fluid pressure regulator, the combination of a housing having a fluid inlet and a fluid outlet, a flow controlling valve, a pressure responsive diaphragm in said housing and operatively connected to said valve, a member located centrally of the diaphragm, spring means for forcing said member toward the diaphragm, radial stems rigidly carried by said member, and eccentric members rotatably mounted on the outer ends of said stems and engaging the diaphragm and said housing.

ANTON SALMONSEN.
